INVENTOR
John Schenk
By Oscar Geiss
ATTORNEY

UNITED STATES PATENT OFFICE.

JOHN SCHENK, OF NEW YORK, N. Y.

WINDOW-SHADE.

1,343,284.

Specification of Letters Patent. Patented June 15, 1920.

Application filed March 6, 1919. Serial No. 281,003.

To all whom it may concern:

Be it known that I, JOHN SCHENK, a citizen of Germany, residing at New York, county of New York, and State of New York, have invented certain new and useful Improvements in Window-Shades, of which the following is a specification.

This invention relates to a mounting for window shades of the ordinary spring roller type and it has for an object to provide a simple and inexpensive device whereby the roller carrying the shade proper, or curtain, may be moved away from the window frame to permit the free passage of air between the shade and window when the latter is open.

A further object is to provide a device whereby this may be accomplished without the employment of additional cords or other hand manipulated devices or parts.

For further comprehension of the invention, and of the objects and advantages thereof, reference will be had to the following description and accompanying drawings, and to the appended claims in which the various novel features of the invention are more particularly set forth.

Figure 1 of the drawings is a perspective view of a window frame and window having my improved shade applied thereto.

Fig. 2 is a face view thereof.

Fig. 3 is a transverse section on the line 3—3 of Fig. 2.

Fig. 4 is an enlarged fragmentary face view thereof.

Fig. 5 is a transverse section on the line 5—5 of Fig. 4.

Fig. 6 is a detail horizontal section through one of the side posts of the upper sash showing a modified form of lifting finger.

In the drawings I have shown a window frame of usual construction comprising the vertical side members 1, and horizontal cross members 2. This frame slidably supports the usual upper and lower window sashes in a well known manner, the upper sash comprising the usual side posts 3, and horizontal bars 4, and the lower sash comprising the usual side posts 5 and horizontal bars 6.

According to my invention I secure to the side members 1 of the window frame a pair of brackets 10 which may be fastened in place by screws 11 or otherwise. Each of these brackets has a socket 12 formed there-

in adapted to pivotally receive the outwardly turned feet 13 of a pair of arms 14 which extend forwardly and upwardly adjacent the window frame member 1, and are formed in their upper ends with heads 15 adapted to support a spring roller 17 in the usual manner, one head being slotted and the other perforated as is well known.

Carried by the side posts 3 of the upper sash members near the tops thereof are hooked fingers 20 whose inturned hooked ends 20' are adapted to engage the arms 14, when the upper sash is closed and swing these arms inwardly so as to bring the shade in close to the top horizontal member 2 of the window frame.

Projecting inwardly from the side frame members 1 are a pair of pins 22 which project across the path of the arms 14 and serve to support the latter when the upper sash is lowered to open the window from the top.

The fingers 20 are preferably so disposed with reference to the arms 14 as to support the latter in a slightly inclined position as shown so that the arms will swing outwardly and downwardly by gravity when the upper sash is lowered until they rest on the pins 22, in which position the shade 17 will be well clear of the frame, as shown in dotted lines in Fig. 3, leaving a space for the passage of fresh air into the room.

As will be apparent my improved device is entirely automatic in action and does not require the manipulation of any extra cords or rods or levers, the shade swinging out when the upper sash is lowered and being swung inwardly again by raising of the sash.

In Fig. 6 I have shown a modified arrangement of the fingers for engaging the arms 14. According to this modification a plate 25 is secured by screws 26 or otherwise on each of the side posts 3 of the upper sash and has its face recessed as at 27. A hooked finger 28 is hinged to this plate as at 29 and is provided with a tail 30 engaging a shoulder 31 on the plate to prevent the finger being swung beyond the perpendicular with respect to the plate.

Should it be desired to raise the lower sash to the top of the frame and lower the upper sash to the bottom of the frame to enable the window to be more easily washed, or for other purposes, the finger 28 on each side post is swung inwardly until it lies in the

recess 27 with its hooked ends 28' projecting inwardly across the edge of the side posts thus permitting free movement of the two sashes.

5 Having thus described my invention, and set forth the manner of its use, what I claim as new, and desire to secure by Letters Patent, is:—

1. A window shade carrying and moving device comprising a pair of arms hinged at their lower ends to the side members of a window frame, said arms being formed to carry a shade on their free ends, members carried by the upper window sash and positioned to engage the said arms to move their shade carrying ends toward the window frame when the upper sash is raised above a predetermined point, said members being arranged to disengage said arms when the upper sash is lowered below said predetermined point.

2. A window shade carrying and moving device comprising a pair of arms hinged at their lower ends to the side members of a window frame, said arms being formed to carry a shade on their free ends, members carried by the upper window sash and positioned to engage the said arms to move their shade carrying ends toward the window frame when the upper sash is raised above a predetermined point, said members being arranged to disengage said arms when the upper sash is lowered below said predetermined point and a pair of projections carried by the side members of the window frame and supporting said arms when the

upper sash is lowered below the said predetermined point.

3. A window shade carrying and moving device comprising a pair of arms hinged at their lower ends to the side members of a window frame, said arms being formed to carry a shade on their free ends, and a pair of hooked fingers fixed to the upper window sash and positioned to engage the said arms to move their shade carrying ends toward the window frame when the upper sash is raised above a predetermined point, said fingers being arranged to disengage said arms when the upper sash is lowered below the said predetermined point.

4. A window shade carrying and moving device comprising a pair of arms hinged at their lower ends to the side members of a window frame, said arms being formed to carry a shade on their free ends, and a pair of hooked fingers fixed to the upper window sash and positioned to engage the said arms to move their shade carrying ends toward the window frame when the upper sash is raised above a predetermined point, said fingers being arranged to disengage said arms when the upper sash is lowered below the said predetermined point and a pair of pins fixed to the side members of the window frame and supporting said arms when the upper sash is lowered below the said predetermined point.

In testimony whereof I have affixed my signature.

JOHN SCHENK.
